UNITED STATES PATENT OFFICE.

RASMUS M. HVID, OF CHICAGO, ILLINOIS, ASSIGNOR TO R. M. HVID COMPANY, OF CHICAGO, ILLINOIS, A CORPORATION OF MICHIGAN.

OIL-BURNING ENGINE.

1,384,376.

Specification of Letters Patent. Patented Mar. 23, 1920.

Application filed January 28, 1918. Serial No. 213,875.

To all whom it may concern:

Be it known that I, Rasmus M. Hvid, a citizen of the United States, and resident of Chicago, in the county of Cook and State 5 of Illinois, have invented certain new and useful Improvements in Oil-Burning Engines, of which the following is a specification.

My invention relates to internal combustion engines and particularly to an improvement in engines of the Hvid type in which ignition is effected by the heat of compression.

An object in the present invention is to 15 provide a simple and effective means for mounting the inlet and exhaust valves and ignition devices in proper relation to the cylinder and piston. In engines of the type referred to a relatively high compression is 20 required which implies the provision of a relatively very small space between the end of the piston and the cylinder head. This makes the location of the inlet and exhaust valves a matter of importance, for while the 25 ports leading to these valves must not be restricted yet the volume of the space must be limited in order to secure the requisite high compression.

Furthermore, the means for effecting 30 ignition in an engine of the type referred to comprises a fuel receiving cup or recess communicating with the combustion space by means of minute apertures and provision must be made for conveniently locating this 35 cup with the required valves in such manner that the full effect of the expansion of the gases may be secured without great heat loss in their passage to the compression space.

40 All of these desired results are secured in the engine illustrated herein, by providing a readily removable cylinder head this head containing the inlet and exhaust ports and valves, the ignition cup and the valves 45 controlling the admission of fuel and air to the cup. This improvement is of particular advantage in connection with horizontal engines but may, with some modifications, be applied to vertical engines. When applied 50 as shown in the drawings, the inlet and exhaust valves are located immediately at the end of the cylinder, no lateral passages from the cylinder being required. By this arrangement the shallow passage leading to 55 the ignition cup may be located almost di-

rectly over the exhaust passage and the heat of the exhaust gases assist in the proper ignition, combustion and expansion of the fuel. Preferably the ignition device is constructed as a unit adapted to be inserted in 60 and removed bodily from the cylinder head as occasion requires.

The invention will be more readily understood by reference to the accompanying 65 drawing, wherein,

Figure 1 is a fragmentary, longitudinal sectional view through a horizontal, oil burning engine constructed in accordance with my invention, and

Fig. 2 is an end view thereof. 70
In the drawings the cylinder is indicated at 10, and the piston at 11. The cylinder head 12, is removably secured to the cylinder by means of bolts 13. The head is provided with water circulation spaces 14, in 75 the usual manner. The inlet and exhaust valves 15, 16, respectively, are located side by side in the head, the valve seats being formed on the portion of the head which actually projects into the end of the cylinder. 80 Therefore no space is wasted in the provision of communicating passages to the valves. The exhaust valve is operated by means of a rocker 17, while the inlet valve is opened by atmospheric pressure following 85 a reduced pressure in the cylinder. An exhaust pipe is shown at 18, and an intake opening at 19. Located above the valves and between the same is a shallow, horizontal passage 20, which communicates with 90 the compression space at the head of the piston and into the inner end of which a cup 21, projects. This cup is secured to the lower end of a plug 22, which is removably 95 mounted within the cylinder head and held by bolts 22^a. The amount of fuel delivered is controlled by the needle valve 23, while the time of delivery of the fuel and a small quantity of air is controlled by the puppet valve 24. Ignition is effected by the use of 100 these instrumentalities in the usual well known manner and they need not be further described.

The fundamental improvement sought to be protected herein is that of providing a 105 readily removable cylinder head and mounting in the head not only the ignition device but the inlet and exhaust valves as well. The construction is more especially adapted to horizontal engines but may be adapted 110

to vertical engines by those skilled in the art. Therefore I do not wish to be limited except as indicated in the claims attached hereto.

I claim:

1. In an engine, the combination with the cylinder and piston, of a removable head having inlet and exhaust ports therein, a relatively shallow, substantially horizontal combustion space in the head, and an ignition unit comprising a plug, a cup at the lower end thereof adapted to project into the combustion space, a needle valve, and a fuel valve for controlling the admission of fuel into the cup, substantially as described.
2. In an oil burning engine, the combination of a cylinder and piston, a removable cylinder head, intake and exhaust valves therein, said head providing a substantially horizontal, shallow combustion space, a fuel cup projecting into said space, and means for supplying fuel to the cup, substantially as described.
3. In a horizontal engine of the type in which ignition is effected by the heat of compression, the combination of a cylinder and piston, a removable head having a shallow horizontal space, a fuel cup projecting into the inner end of said space, means carried by the head for controlling the admission of fuel into said cup, and inlet and exhaust valves in said head, substantially as described.
4. In an oil burning engine, the combination of a cylinder and piston, a cylinder head, said head having a relatively shallow horizontal space, a fuel-receiving cup mounted at the inner end of said space, the bottom wall of said cup being horizontally disposed, and means for supplying liquid fuel to said cup, substantially as described.
5. In an oil burning engine, the combination with the cylinder and piston, of a removable head, inlet and exhaust valves in said head, said valves being positioned in close proximity to the end of the piston at the point of its extreme travel, the head being provided with a relatively shallow, horizontally disposed space located at one side of and between said inlet and exhaust valves, a fuel-receiving cup disposed at the inner end of said space, and means for feeding liquid fuel to said cup, substantially as described.
6. In an internal combustion engine, the combination with a cylinder and piston of a cylinder head having a shallow, horizontal passage, and an igniting device including a plug adapted to be fitted into a suitable recess in said head, a fuel-receiving cup associated with the plug, the floor of the cup being horizontally disposed and the plug being so positioned as to locate the cup at the inner end of said passage, said cup being provided with a relatively small aperture which opens into the passage and is so arranged as to discharge fuel in line with said passage and toward the end of the piston, substantially as described.
7. In an internal combustion engine, the combination with a cylinder and piston of a cylinder head having a shallow, horizontal passage, a liquid fuel receiving cup having side walls and a floor, said cup being located in the inner end of said passage with its floor in a horizontal position, a side wall of the cup being provided with an aperture located near the floor, the aperture being positioned to cause the discharge of atomized liquid fuel in line with the longitudinal axis of the passage and toward the end of the piston, substantially as described.
8. In a hydrocarbon engine, the combination with the cylinder and piston of a removable cylinder head having a portion fitting the open end of the piston, inlet and exhaust ports in said portion, valves for closing said ports, the head being provided with a shallow, horizontal passage the entrance to which is in said portion at a point between and at one side of said ports, and a fuel cup having a horizontal floor located at the inner end of said passage, substantially as described.

Signed at Chicago, Ill., this 17th day of January, 1918.

RASMUS M. HVID.
